UNITED STATES PATENT OFFICE.

EMIL WEBER AND FRANK C. FREY, OF BAKER CITY, OREGON.

LOCK.

SPECIFICATION forming part of Letters Patent No. 700,106, dated May 13, 1902.

Application filed June 15, 1901; Serial No. 64,739. (No model.)

To all whom it may concern:

Be it known that we, EMIL WEBER and FRANK C. FREY, citizens of the United States, residing at and whose post-office address is 5 1933 Court street, Baker City, in the county of Baker and State of Oregon, have invented new and useful Improvements in Locks, of which the following is a specification.

Our invention relates to locks of the class 10 which are especially adapted for use as door-locks; and its primary object is to entirely avoid the employment of springs and to thus greatly simplify this class of locks.

A further object of the invention is to provide 15 a lock which cannot be opened by any means other than a key specially constructed and adapted for the purpose.

The invention comprises a gravity-operated bolt, a tumbler coacting therewith and adapted 20 to be oscillated by a key, pins within the tumbler, and a double-acting locking-dog for controlling the movement of the tumbler.

The construction of the improved lock will be fully described hereinafter in connection 25 with the accompanying drawings, which form part of this specification, and its novel features will be defined, and particularly pointed out in the appended claims.

In the drawings, Figure 1 is an elevation 30 of a lock embodying the invention, the cover-plate of the casing being removed and the bolt being shown in locked position. Fig. 2 is a similar view showing the position of the parts when unlocked. Fig. 3 is a detail perspective of the oscillating tumbler forming 35 an element of the lock. Fig. 4 is a vertical sectional view of the tumbler, and Fig. 5 is a view in perspective of the locking-dog.

The reference-numeral 1 designates the 40 lock-casing, the face-plate 2 of which is formed with the usual bolt-slot 3. Within the casing is pivotally secured by a pin 5 a swinging quadrant 4, formed with two segmental slots 6 and 7, through which extend stop-pins 8 and 9. The quadrant 4 is also provided with a 45 oblong recess 10, within which extends a lever 11, mounted upon a revoluble sleeve 12, through which the knob-shaft is adapted to extend. The ends of the recess 10 are curved 50 to permit the required movement of the lever.

13 designates the lock-bolt, provided with a stem 14, extending through an opening in

the front face of the quadrant 4 into the slot 7, where it is secured by a cross-pin 15. The inner edge of the quadrant 4 is formed with 55 a segmental seat 16, within which is adapted to fit a segmental tumbler 17, mounted upon an oscillating sleeve 18, formed with a key-slot 19. The movement of the tumbler 17 is limited by a stop-pin 20, against which the 60 curved face 21 of the tumbler bears, and said tumbler is formed with a shoulder 22, adapted to be engaged by a dog 23, pivotally secured to the casing. The dog 23 is formed with a segmental recess providing a shoulder 65 24 for a purpose hereinafter explained. The tumbler 17 is formed with a plurality of parallel openings 25, within each of which is arranged a movable pin 26, said pins being suitably guided, preferably by lugs 27, moving 70 in recesses formed in the walls of the openings 25.

The operation of the mechanism above described may be explained as follows: As will be apparent from the illustration in Fig. 1, 75 the weight of the quadrant 4 holds the bolt 13 normally in its projected or locked position, and the engagement therewith of the tumbler 17 (the latter being held by the engagement of the dog 23 with the shoulder 22) 80 maintains the bolt in locked position. The pins 26 are of varying length and any desired number and are adapted to be lifted by the contact therewith of a suitably-notched key. The lifting of the pins by the insertion of the 85 key within the key-slot 19 forces their outer ends against the under surface of the dog 23 to disengage the latter from the shoulder 22 and permit the sleeve 18 and the tumbler 17 to be turned to the position shown in Fig. 2. 90 After the tumbler has been thus turned the bolt may be withdrawn by swinging the quadrant 4 inward upon its pivot through the medium of the lever 11, carried by the sleeve 12, the latter being oscillated by the turning of 95 the knob-shaft extending therethrough.

An important feature of the invention is the double-acting dog 23, having the shoulder 24, as said dog not only normally engages the quadrant 4 to hold the parts in locked position, but also serves as a security against unauthorized opening or tampering with the lock. If any key or instrument other than the key specially constructed for the purpose

is inserted into the key-slot 19, all of the pins 26 will not be lifted and the dog 23 will be so tilted that its shoulder 24 will engage the inner projecting curved edge 28 of the tumbler.

5 It will thus be seen that the lock is secure and cannot be picked or tampered with.

A distinguishing characteristic of the improved construction is that we entirely avoid the use of springs for projecting or retracting the bolt.

While we have shown a lock in which a revoluble sleeve is employed in connection with a knob, it is obvious that a pivoted lever or latch for raising the quadrant 4 may be readily substituted in lieu of the lever and sleeve shown. This construction we may find desirable or convenient in connection with store-door locks or where a knob would not be conveniently used.

20 The lock constructed as above described is of few parts, so combined as to insure ready operation and durability in use.

We claim—

1. The combination with a quadrant provided with a latch-bolt and a segmental seat, of an oscillating sleeve having a key-slot and provided with a segmental tumbler to normally engage said seat, said tumbler having a shoulder and parallel openings having recesses and extending from the rear of said shoulder to the key-slot, pins of varying length movably mounted in said openings and provided with lugs to work within said recesses, a stop-pin to limit the movement of said tumbler, and a dog to engage shoulder to hold the tumbler normally in engagement with said seat, and having a segmental recess providing a shoulder to engage the in-

ner projecting curved edge of said tumbler when a false key is inserted into the key-slot. 40

2. The combination with a casing, of a pivoted quadrant adapted to swing therein, provided with segmental slots 6 and 7, an oblong recess and a segmental seat, pins extending in said slots to limit the movement of the quadrant, an operating-lever working within the recess, a latch-bolt having a stem extending through an opening in the quadrant into the segmental slot 7, a pin holding said latch-bolt therein, an oscillating sleeve having a key-slot and provided with a segmental tumbler to normally engage said seat, said tumbler having a shoulder and parallel openings having recesses and extending from the rear of said shoulder to the key-slot, pins of varying length movably mounted in said openings and provided with lugs to work within said recesses, a stop-pin to limit the movement of said tumbler, and a dog to engage said shoulder to hold the tumbler normally 60 in engagement with said seat, and having a segmental recess providing a shoulder to engage the inner projecting curved edge of said tumbler when a false key is inserted in the key-slot. 55

In testimony whereof we affix our signatures in presence of witnesses.

EMIL WEBER.
FRANK C. FREY.
